PETER COOPER HEWITT, OF NEW YORK, AND NELSON W. ROGERS, OF MOUNT VERNON, NEW YORK, ASSIGNORS, BY MESNE ASSIGNMENTS, TO COOPER HEWITT ELECTRIC COMPANY, OF HOBOKEN, NEW JERSEY, A CORPORATION OF NEW JERSEY.

ELECTRIC GAS OR VAPOR LAMP.

1,079,342.

Specification of Letters Patent. Patented Nov. 25, 1913.

Original application filed March 23, 1901, Serial No. 52,499. Divided and this application filed November 16, 1906. Serial No. 343,699.

To all whom it may concern:

Be it known that we, PETER COOPER HEWITT and NELSON W. ROGERS, citizens of the United States of America, and residents, respectively, of New York, in the county of New York and State of New York, and Mount Vernon, in the county of Westchester and State of New York, have invented certain new and useful Improvements in Electric Gas or Vapor Lamps, of which the following is a specification.

Our invention relates to the class of apparatus for electric lighting in which electric energy is converted into light through the agency of vapors or gases.

In a certain other application for Letters Patent filed by Peter Cooper Hewitt on April 5th, 1900, Serial No. 11,605, he has described a form of lamp using a vapor or gas as a light-emitting element. In certain forms of lamps of this character, there is found to be a reluctance on the part of the lamp to light up under the influence of the normal operating electromotive force of the lamp. This reluctance exists at and around the negative electrode. He has provided various means for affording an initial starting impulse, or series of impulses, of higher electromotive force for breaking down this reluctance whereupon the current will continue to flow under the influence of the normal difference of electric potential.

Our present invention involves the use of a supplemental starting electrode for overcoming the electrode reluctance and for placing the lamp in a condition to be traversed by the normal current. This supplemental electrode is placed in relatively close proximity to the working negative electrode, and an electric current is caused to pass from the supplemental electrode to the adjacent working electrode in any suitable manner; for instance, by bringing the two temporarily into actual contact, or by bridging the space between the two by a good electric conductor, and then separating them when the current is flowing. When current is thus caused to flow from one electrode to the other the negative electrode reluctance to starting being overcome, the remote electrode may be substituted for the starting electrode and the current caused to pass

readily between the two working electrodes, as only the vapor then forms the resistance. It is usually found advantageous, however, in substituting the second working electrode for the starting electrode, to cause a momentary electromotive force of somewhat higher potential than the normal working potential for insuring the substitution.

In the accompanying drawings, illustrating the invention Figure 1 illustrates one form of lamp embodying the invention and Fig. 2 illustrates a modification in the general arrangement of circuits and apparatus.

Referring to the drawings, 1 represents the inclosing chamber of the lamp which may be of glass or other transparent material and containing a suitable gas or vapor. It is shown as being provided with an enlargement, 4^a, for increasing the heat-radiating capacity of the lamp; this enlargement also serving to contain any slight impurities which may develop in the lamp.

The tube is provided with two working electrodes 2 and 5. When the lamp is operated by continuous currents the electrode 2 is the positive electrode and the electrode 5 the negative electrode. The positive electrode may be of iron or other suitable material. The negative electrode may consist of a small quantity of mercury through which projects a point of solid material, 75 when the vapor path of the lamp is to be of mercury vapor. An auxiliary positive electrode, 2^a, is shown as being placed in the enlargement 4^a, in proximity to the negative electrode 5 and capable of making actual contact therewith. The electrode 2^a may be supported in any convenient manner so that it may be moved away from the electrode 5 in any convenient manner as, for instance, by means of a magnet, 20, the coils of which are included in a conductor, 21, leading from the electrode 2^a to the positive main conductor 14. The negative electrode 5 is connected by a conductor, 22, with the negative main conductor, 15. There may also be included in the conductor 21, a reactive coil 17 or other suitable device for causing a momentary impulse of high electromotive force. A conductor, 23, leads from a point 24, in the conductor 21, to the positive electrode 2. An electromagnet 25 is included

in the conductor 23, and its armature 26, is employed for operating a switch 27 through which the connections of the conductor 21 are completed when the apparatus is not in operation. This armature 26 is shown as being provided with a counterweight 28, for the purpose of rendering its operation somewhat sluggish for the purpose of introducing a time element in its operation, it usually being desirable that the switch should respond to the action of the magnet 25, subsequently to the action of the magnet 20.

The operation of the lamp is as follows: Assuming that the circuit connections between the conductors 21 and 22 and the main lines 14 and 15 are closed by means of a switch 29, then current will pass through the conductor 21 to the positive electrode 2^a, thence to the electrode 5, with which it is in contact, and by way of the conductor 22 back to the line 15. A suitable resistance 30 may be included in the conductor 21 in addition to the resistance offered by the electromagnet 17, if desired, for preventing too great a flow of current through this circuit. Thereupon the electromagnet 20, will separate the electrode 2^a from the electrode 5. This separation causing a variation in the resistance of the circuit, will result in a high potential discharge from the coil 17 through the conductor 23, to the electrode 2 and through the tube to the negative electrode 5. This discharge will then be accompanied by a flow of current from the main circuit through the entire tube between the electrodes 2 and 5. Thereupon the current flowing through the coils of the magnet 25 will operate the switch 27, and thus interrupt the circuit connections of the conductor 21 to the electrode 2^a, the circuit then being from the main line through a portion of the conductor 21, the coil 17, the energized magnet 25, the conductor 23 to the positive electrode 2, thence through the lamp to the negative electrode 5, and by way of the conductor 22 to the negative main wire 15. Meanwhile, the electrode 2^a will return to its normal position, the circuit through the magnet 20 having been interrupted so that in case the circuit is elsewhere interrupted and the switch 27 returned to its original position, the circuit may be again completed through the electrode 2^a as before.

The coil 17 may be allowed to remain in circuit and serve as a steadyng-resistance for the lamp, or an additional steadyng-resistance may be included in the conductor 23, for instance, as indicated at 31. The coil 17, however, has an additional advantage over an ordinary ohmic resistance in that it serves to compensate for any temporary variations in the line voltage. For instance a sudden fall in the line potential would result in a momentary increase in the potential applied to the terminals of the

lamp by reason of the discharge of the core, and, likewise, when any sudden increase in the line voltage occurs, the coil, 17, will tend to check the application of this increase to the terminals of the lamp.

In Fig. 2 a modification is shown wherein in the conductor 21 is connected to a point 32, of a switch 27 operated by the magnet 25. A second contact point 33, of this switch is connected by the conductor 21^a, 70 through the coil 17 with the conductor 14 as before. In this instance the coil 17 acts as a primary of a converter, the secondary coil 18 of which is connected in the reverse direction from the coil 17 and in the conductor 23 leading to the positive electrode 2. A shunt circuit, 34, is provided around the secondary coil 18, its connections being interrupted when the apparatus is in the position shown in the drawing at the point 35, at which point a circuit closer is represented for completing the shunt connections when the magnet 25 is energized and the circuit connections 32 and 33 are interrupted. A resistance 31 is included in the conductor 34, and this may be either an ohmic resistance or an inductive resistance as desired. We have also shown in this figure a resistance, 36, in shunt around the magnet 20 for the purpose of permitting the use of a smaller magnet for operating the electrode 2^a. The operation of this apparatus is essentially the same as that described with reference to Fig. 1. Upon the closing of the circuit of the conductors 21^a and 22^a, the current passes through the coil 17, the contact point 33, switch arm 27, contact point 32, and by way of wire 21 and magnet 20, to the electrode 2^a, whence it passes to the electrode 5 and the conductor, 100 22^a. Upon the separation of the electrodes 2^a and 5, by the action of the magnet 20, a variation of the resistance in the circuit takes place, affecting the coil 17, and through that causing an impulse of high 110 potential to be excited in the secondary 18, whereupon a high potential discharge takes place through the circuit 23, including the magnet 25, passing through the lamp from the electrode 2 to the electrode 5, and out 115 as before. The current which is then caused to flow through the circuit including the apparatus and the magnet 25 acts to open the circuit at the contact points 32, 33, and to close a circuit at the point 35, by a pulling down of the switch arm 27. The secondary 120 18 is thus short circuited by the wire 34, including the resistance 31, and the lamp continues to operate upon a circuit including the wire 34, and its resistance 31, the 125 contact 35 and magnets 25, the rest of the circuit being completed as before. The resistance 31 is so adjusted that the ballast effect of the devices remaining in the circuit will be properly proportioned to the 130

requirements of the circuit upon which the apparatus is operated.

In practice we have found that by starting the lamp by first making a temporary connection between the starting electrode and the negative electrode and then separating it, the reluctance of the passage of the current through the entire lamp is very much diminished and, therefore, a relatively small discharge impulse suffices to secure the passage of the current through the lamp. The reactive device may therefore be made small or even dispensed with in some instances. The substitution of the positive electrode 2 for the temporary positive electrode is facilitated by the use of a conducting band 9 placed outside the tube at or near the negative electrode and connected either with the ground or with a conductor leading to the positive electrode. We have also found that the presence within the tube of a starting material, such for instance, as a small amount of sulfur also serves to facilitate this substitution.

While the apparatus herein illustrated is primarily designed for light-giving purposes, yet it is evident that the action of the parts constituting the present invention would be the same whether the device were used as a lamp or for any other of the purposes for which vapor apparatus of this class is suited.

It will be seen that the part 2^a which has been called an auxiliary positive electrode constitutes, with the electrode 5, a switch inside the container, the same being adapted to be operated by the action of the magnet 20. It will also be seen that when the main switch 29 is closed the circuit including the described switch is in shunt to the main lamp circuit and that when the magnet 20 operates to open the switch the shunt circuit is broken. As a result of this operation the reactive coil 17 impresses upon the main circuit including the gas or vapor apparatus a temporary impulse of high potential tending and operating to start the apparatus.

This application is a division of an application filed by us March 23, 1901, Serial Number 52,499.

We claim as our invention:

1. The method of starting a gas or vapor electric apparatus having electrodes, one at least of which is composed of vaporizable material and having an auxiliary means for initially producing a local vaporization of vaporizable material at the last named electrode, which consists in initially causing a localized vaporization by means of a supplementary electrode and afterward transferring the flow of current to the other working electrode.

2. In a gas or vapor electric apparatus of the character described, having one negative

electrode and at least two positive electrodes, one positive electrode being adapted for electrical connection within the container with the negative electrode, the method of starting operation, which consists in automatically overcoming the negative electrode resistance by a supplementary flow of current, and thereafter transferring this current flow to the main path through the agency of a temporarily impressed higher potential impressed thereon.

3. The method of starting and operating gas or vapor electric apparatus having electrodes, one at least of which is formed wholly or in part of vaporizable material, and having auxiliary means for initially producing a localized vaporization of the material forming said vaporizable electrode, which consists in initiating a vaporization locally by means of a supplementary electrode, and thereafter transferring the flow of current from the local to the other working electrode.

4. The method of producing a flow of current in an evacuated space between electrodes, one at least of which during said flow of current emits a vapor, which consists in impressing upon said electrodes through two paths an electromotive force of a value insufficient to initiate the desired flow of current and, disengaging from the vapor emitting electrode migratory ions in one of said paths by an electromotive force of the same order of magnitude as that applied to the main electrodes.

5. The method of starting a vapor electric apparatus having main electrodes and an additional or auxiliary electrode adapted to co-operate therewith, which consists in impressing upon a main electrode and said additional electrode an electromotive force, and by the action of said electromotive force causing an initial production of ionized vapor.

6. The method which consists in generating a supplementary arc, causing the main arc to start from the negative terminal of the supplementary arc, and automatically interrupting the supplementary arc when the main arc starts.

7. The method of operating a vapor electric apparatus having main positive and negative electrodes and a supplementary positive electrode, which consists in making and breaking contact between said supplementary electrode and the negative electrode to produce a starting arc, continuing the starting arc until the main arc forms from said negative electrode, and automatically interrupting the current flowing to said starting arc.

8. The method of operating a vapor electric apparatus, which consists in causing current to flow in a supplementary circuit in the apparatus and thereby forming a

starting arc, causing thereby the main arc to start from the negative terminal of the starting arc, and controlling the flow of current to the starting arc by current flowing 5 in the main arc.

9. The method of operating a vapor electric apparatus from a source of direct current, which consists in generating by the action of a supplemental current a starting 10 arc, continuing said starting arc until the main arc forms, and discontinuing the starting arc in response to the flow of the main arc current.

10. The method of operating a vapor electric apparatus provided with a main circuit 15 and a supplemental circuit, which consists in first causing current to flow in the supplemental circuit so as to form a starting arc, continuing the starting arc until the main arc forms from the negative terminal 20 of the starting arc, and then interrupting said supplemental circuit in response to flow of current in the main circuit.

11. The method of starting and operating 25 gas or vapor electric apparatus having electrodes, one at least of which is formed

wholly or in part of vaporizable material, and having auxiliary means for initially producing a localized vaporization of the material forming said vaporizable electrode, 30 which consists in initiating a vaporization locally by means of a supplementary electrode, and thereafter transferring the flow of current from the local to the other working electrode. 35

12. The method of starting a vapor electric apparatus having main electrodes and an additional or auxiliary electrode adapted to coöperate therewith, which consists in impressing upon a main electrode and said 40 additional electrode an electromotive force causing an initial production of ionized vapor.

Signed by us at New York, in the county of New York, and State of New York, this 45 13th day of November, A. D., 1906.
